SHEET FEEDING APPARATUS

Edwin W. Goodwin, New Rochelle, N. Y., assignor
to Dexter Folder Company, Pearl River, N. Y.,
a corporation of New York

Application March 26, 1940, Serial No. 325,981

23 Claims. (Cl. 271—62)

This invention relates to sheet feeders and more particularly to pile or sheet supply elevating or moving mechanism and control means therefor.

One object of the present invention is to provide a sheet feeder having improved mechanism for intermittently operating the pile or sheet supply elevating or moving means.

Another object of the present invention is to provide a sheet feeder having novel means of smooth and positive action for controlling the operation of the pile or sheet supply elevating or moving mechanism.

Another object of the present invention is to provide a sheet feeder having improved mechanism for actuating the pile or sheet supply elevating or moving means, and which may be thrown out of operation when testing or adjusting the various operating parts of the feeder or the machine with which the feeder is associated.

Another object of the present invention is to provide a sheet feeder having separate and improved mechanisms for intermittently or continuously operating the pile or sheet supply elevating or moving means and novel means for preventing simultaneous operation of said mechanisms.

These and other objects of the present invention will appear as the following description thereof proceeds and in order to more clearly understand said invention reference may be had to the accompanying drawings which illustrate one embodiment thereof.

In said drawings:

Fig. 1 is a side elevation of a sheet feeder constructed in accordance with the present invention and including a pile elevator;

Fig. 2 is a fragmentary front elevation of the sheet feeder shown in Fig. 1;

Fig. 3 is an enlarged fragmentary side elevation, partly in section, of the upper part of said sheet feeder, showing pile height governing means and the parts of pawl and ratchet actuated pile elevator operating mechanism thrown into inoperative positions by said pile height governing means;

Fig. 4 is a detail perspective view of pile height governed pawl control means with elements thereof spread apart for purposes of clearer illustration;

Fig. 5 is a view similar to Fig. 3 but showing the parts of the pawl and ratchet actuated pile elevator operating mechanism thrown into operative positions by the pile height governing means;

Fig. 6 is an enlarged fragmentary side elevation of a lower part of the sheet feeder, showing a manually operated unit for controlling operation of the pile elevator;

5 Fig. 7 is a transverse vertical sectional view on the line 7—7 of Fig. 6, the parts of the manually operated unit in this figure as well as in Fig. 7 being shown in neutral positions where they prevent operation of the pile elevator;

10 Fig. 8 is a view similar to Fig. 7 but showing the parts of said unit actuated to positions enabling the pile elevator to be operated only by the pawl and ratchet actuated elevator operating mechanism;

15 Fig. 9 is a view similar to Figs. 7 and 8 but showing in full line and dotted lines the parts of said unit actuated to positions enabling the pile elevator to be operated only by rapid raising or lowering means employed when loading or re-

20 loading said elevator;

Fig. 10 is an enlarged detail perspective view of an elevator control member or cam shown in Figs. 6 to 9 inclusive; and

Fig. 11 is an enlarged detail view of pile and 25 manually actuated pile elevator and motor control devices, illustrating diagrammatically an electric circuit therefor.

Referring to the drawings, wherein like reference characters designate like parts throughout the several views, the various movable parts of the feeder, as well as certain stationary parts thereof, may be mounted on a frame of any suitable construction and the movable parts employed during normal operation of the feeder may 30 be actuated or driven by any suitable means. As herein shown, said frame and driving means are preferably constructed and operated, respectively, as follows.

The feeder frame is comprised by front up- 40 rights 5 and rear uprights 6 at opposite sides of the feeder, the front uprights 5 having heads 7 bolted or otherwise suitably secured thereto and the rear uprights 6 having heads 8 bolted or otherwise suitably secured thereto (Figs. 1, 2, 3 and 5). The lower ends of uprights 5 and 6 are bolted or otherwise suitably secured in brackets 9 and 10 respectively which, in turn, are bolted or otherwise suitably secured to the machine foundation. The heads 7 and 8 are connected together by side members 11 bolted or otherwise suitably secured thereto. The front heads 7 are connected together by a stay shaft 12, a cross bar 13 and a cross tube 14 which are bolted or otherwise suitably secured to said heads, and the rear heads 8 are connected together by a stay shaft 55

15 bolted or otherwise suitably secured thereto. Referring now more particularly to Figs. 1 and 2, the drive for the feeder is preferably comprised by a chain 16 driven from any suitable source of power (not shown) and passing around a sprocket 17 which is fixed on one end of a shaft 18 extending transversely of the feeder and journalled in suitable bearings in brackets 19 and one of the front heads 7. The brackets 19, located at opposite sides of the feeder, are spaced inwardly from the front heads 7 and are secured in any suitable manner to said heads. Fixed on the opposite outwardly projecting end of the shaft 18 adjacent one of the front heads 7 is a spur pinion 20 which meshes with and drives a spur gear 21 in the direction of the arrow indicated in Fig. 1. This spur gear 21 is fixed on and drives a transversely extending cam shaft 22 which is journalled in suitable bearings in the front head 7 and the brackets 19. Cam shaft 22 is utilized to operate various parts of the feeder to be hereinafter described.

Extending longitudinally of the feeder near the top and at opposite sides thereof are shafts 23 (Figs. 1 and 2) which are journalled in suitable bearings formed in the front heads 7 and in brackets 24 that are bolted or otherwise suitably secured to the side members 11. Fixed on the shafts 23 are sheaves 25 in the teeth of which are engaged links of vertically extending chains 26 that pass around said sheaves. The chains 26 are connected at their lower ends, as by couplings 27, to the side members 28 of a pile elevator including cross beams 29 engaged over said side members and adapted to receive and support a pile board 30 and pile of sheets 31 thereon. The shafts 23 are intermittently rotated during the operation of the feeder by mechanism that will be hereinafter described and which acts to raise the pile elevator step by step in order to maintain the top of the pile at a proper level and thus insure continuous and accurate separation and feeding of the sheets from the top of said pile. During step by step upward movement of the elevator the front of the pile is guided by spaced vertical pile guides 32 which are clamped in any suitable manner at the upper and lower ends thereof to the stay shaft 12 and a stay shaft 33 extending transversely of the feeder and fixed in the brackets 9.

The sheets are separated one after another from the top of the pile and may be forwarded therefrom either singly in spaced relation or, as herein shown, in continuous stream form and underlapped relation. Referring to Fig. 1, the sheets are separated one after another from the top of the pile 31 at the rear and opposite sides thereof by sheet separating mechanisms preferably of the general type disclosed in my application Serial No. 267,963 filed April 15, 1939. These sheet separating mechanisms are located adjacent the upper rear corners of the pile of sheets and each include suction sheet separating means comprised by a conduit 34, an arcuate housing 35 connected therewith, and a tubular arcuate member 36 slidable in the housing 35 and provided on the lower end thereof with a rubber suction cup 37. Vacuum is created in the arcuate housings 35 at predetermined intervals to cause the suction cups 37 to grip opposite rear corners of the successive sheets and lift the rear edges thereof above the level of the pile. For this purpose, the conduits 34 have connected therewith corresponding ends of flexible conduits 38 the opposite ends of which are connected in any

suitable manner with a rotary valve mechanism indicated broadly at 39 (Figs. 3 and 5) that, in turn, is connected by a conduit 40 (Fig. 2) with the vacuum side of a combined air and vacuum pump 41. The rotary valve mechanism 39 is mounted at the rear of the feeder approximately in the center thereof on a transversely extending hollow square bar 42 and a longitudinally extending bar 43 supported in any suitable manner on the feeder frame. The rotary valve mechanism 39 is substantially the same in construction and operation as the rotary valve mechanism disclosed in the United States Patent No. 2,156,648 granted May 2, 1939 to Leonard Baker, George A. Martin and Leo C. Williams and needs no detail description herein.

The pump 41 is bolted or otherwise suitably secured to a platform 44 (Figs. 1, 2 and 6) extending transversely of the feeder at the front 20 and bottom thereof and supported at its opposite ends on short shafts 45 that are secured in any suitable manner in the brackets 9. Connected with the air side of pump 41 is one end of a conduit 46 the opposite end of which is connected with a compressed air tank 47 (Fig. 2) that is mounted on, and secured in any suitable manner to, the under side of the platform 44. This air tank 47 is, in turn, connected by a conduit 48 with pile and sheet winding devices (not 25 shown) that supply air under pressure for winding the uppermost sheets of the pile prior to action thereon by the suction cups 37, and for winding each separated sheet to completely 30 separate the same from the pile and assist forwarding of the sheet by suction sheet forwarding devices hereinafter described.

Prior to release of the separated and lifted sheet by the suction cups 37, said sheet is gripped at spaced points across the rear thereof by suction sheet forwarding devices indicated broadly at 49 (Fig. 1) which are preferably mounted, constructed and operated in the same manner as the suction sheet forwarding devices disclosed in my application Serial No. 267,963 mentioned 45 above. These sheet forwarding devices are comprised by cylinders 50 and rubber suction cups 51 which are vacuum operated in opposite directions to engage and lift each separated sheet. The cylinders 50 are carried in the free ends of 50 horizontal arms 52 which are pivotally connected to the lower ends of vertically extending parallel arms 53 and 54 that impart horizontal reciprocating motion to the suction sheet forwarding devices 49. The arms 53 are adjustably secured to a transversely extending rock shaft 55 which is journalled in suitable bearings formed in brackets 56 at opposite sides of the feeder. The arms 54 are rotatably mounted on a transversely extending shaft 57 that is secured in said brackets. Through operation of the rotary valve mechanism 39 vacuum is created in the cylinders 50 at predetermined intervals to cause the suction cups 51 to grip each sheet lifted by the separator suction cups 37 and for this purpose, 60 said cylinders have connected therewith corresponding ends of flexible conduits 58 the opposite ends of which are connected in any suitable manner with the rotary valve mechanism 39.

The suction sheet separating and forwarding devices and the rotary valve mechanism are operated from the cam shaft 22 by a suitable driving mechanism constructed and arranged in the same manner as the driving mechanism disclosed in my application Serial No. 267,963 mentioned above. This driving mechanism includes

a bevel gear 59 (Fig. 2) fixed on the cam shaft 22 and which meshes with a similar gear 60 that is fixed on the lower end of a vertical shaft 61 journaled at one side of the feeder in suitable bearings on one of the front heads 7. The vertical shaft 61 has fixed on the upper end thereof a bevel gear 62 which meshes with a similar gear 63 that is fixed on the forward end of a horizontally extending shaft 64 located at the top and one side of the feeder and journaled in suitable bearings on the feeder frame. This shaft 64 through suitable connections (not shown) actuates the forwarder rock shaft 55 and drives a transversely extending shaft 65 (Figs. 3 and 5) which is connected with and operates the rotary valve mechanism and the suction sheet separating devices.

Each sheet gripped by the suction sheet forwarding devices 49 is forwarded thereby from the pile under and in lapped relation with a preceding sheet to conveying means continuously driven at slow speed to enable lapping of the sheets thereon. As shown in Figs. 1 and 2, this conveying means comprises a feed roller 66 and pressure rollers 67 cooperating with said feed roller to receive the forwarded sheets in lapped relation and advance said sheets to slow moving tapes 68 that convey a stream of the lapped sheets to a printing press or other machine with which the feeder is associated. The feed roller 66 extends transversely of the feeder and is journaled in suitable bearings in the brackets 19. The pressure rollers 67 are journaled on arms 69 adjustably secured on a cross shaft 70 having its opposite ends mounted in any suitable manner in the brackets 19. An additional support for the pressure roller shaft 70 is provided by a bracket 71 (Figs. 2 and 11) located intermediate the ends of said shaft and bolted or otherwise suitably secured to the cross bar 18 and cross tube 14. The front ends of the tapes 68 pass around a suitable roller or rollers (not shown), and the rear ends of said tapes pass around and are driven by a roller 72 that extends transversely of the feeder and is journaled in suitable bearings in the brackets 19.

The feed roller 66 and the tape roller 72 are driven continuously and at slow speed from the cam shaft 22 by a spur gear 73 (Fig. 2) fixed thereon adjacent the inner side of one of the brackets 19 and which meshes with a similar gear 74 that is fixed on a short shaft 75. This short shaft 75 is journaled in suitable bearings formed in one of the brackets 19 and the adjacent front head 7, and said shaft has also fixed thereon adjacent the outer side of said bracket a spur gear 76. This spur gear 76 meshes with an idler gear 77 which is journaled in any suitable manner on the bracket 19. The idler gear 77, in turn, meshes with and drives spur pinions 78 and 79 (Figs. 1 and 2) that are fixed on the outwardly projecting ends of the feed roller 66 and tape roller 72, respectively.

During normal operation of the feeder the elevator chain shafts 23 are operated intermittently to raise the pile elevator and pile of sheets at suitable intervals. This intermittent operation of shafts 23 is effected by pawl and ratchet mechanism preferably mounted, constructed and operated as follows. Secured to or formed integrally with the spur gear 24 and rotated continuously thereby is a crank disc 80 (Figs. 3 and 5) having pivotally connected therewith one end of a link 81 the opposite end of which is pivotally connected with a reciprocated pawl carrier 78

82. The pawl carrier 82 is loosely mounted on the outwardly projecting end of a shaft 83 and is continuously oscillated thereon. This shaft 83 extends transversely of the feeder and is journaled in suitable bearings formed in brackets 84 that are bolted or otherwise suitably secured to the front heads 7. Additional bearings for the shaft 83 are provided by the brackets 19 and the center bracket 11. The pawl carrier 82 has pivoted thereon at 85 a spring pressed pawl 86 adapted, under certain conditions, to engage a ratchet 87 fixed on the shaft 83 outwardly of said carrier and so disposed that the outer face of said ratchet is substantially flush with the end of said shaft. It will thus appear that through oscillation of the pawl carrier 82 by the crank disc 80, and engagement of the oscillating pawl 86 with the ratchet 87, the shaft 83 will be intermittently rotated. Under these conditions, a worm 88 (Fig. 2) fixed on each end of the shaft 83 and located in a suitable opening in the adjacent front head 7 will likewise be rotated. Each worm 88 meshes with and drives a corresponding worm gear 89 that is fixed on the forward end of each elevator chain shaft 23 and also located in a suitable opening in the adjacent front head 7. Step by step elevation may thus be imparted to the elevator and pile of sheets thereon by the shafts 23 through the described driving connections therefor with the worm shaft 83.

As the sheets are fed off the top of the pile 31 by the described separating and forwarding devices the elevator and pile of sheets thereon are raised intermittently by the described pawl and ratchet mechanism, and to keep the top of the pile at a predetermined level for action thereon by the sheet separating and forwarding devices the elevator and its intermittently actuated operating mechanism are, in accordance with the present invention, controlled by novel means preferably mounted, constructed and operated as follows. The crank disc 80 (Figs. 3, 4 and 5) has formed integrally therewith a cam 90 which engages a roller 91 journaled on a stud 92 that is secured in any suitable manner in one arm 93 of a double armed lever 94 (Fig. 4) the other arm of which is indicated at 95. The double armed lever 94 is pivotally mounted on a laterally projecting stud 96. This stud 96 is located beneath the ratchet 87 in vertical alignment with the axis of said ratchet and the shaft 83 and is secured in any suitable manner in the adjacent front head 7. The arm 93 has pivotally connected therewith at 97 a vertically disposed spring pressed rod 98 provided on the upper reduced end thereof with a sleeve 99 that is guided for vertical movement in a lug 100 formed on and projecting laterally from a bracket 101 bolted or otherwise suitably secured to the adjacent front head 7. The sleeve 99 is secured on the rod 98 by a threaded nut 102, and accidental rotation of said sleeve on said rod is prevented by a pin 103 adjustably secured in the lug 100 and engageable with a flattened portion 104 formed on the sleeve. The spring 105 for rod 98 is mounted thereon between a collar 106 secured to said rod and a forked stud 107 secured in any suitable manner in the bracket 101 and through which the rod extends. It will thus appear that the double armed lever 94 and the sleeve 99 are cam operated in one direction and spring operated in the opposite direction by the cam 90 and the rod 98, respectively.

Pivotedly mounted on the outer end of the

stud 96 adjacent the double arm lever 94 is a lever 108 that has bolted or otherwise suitably secured thereto a controlling finger 109 which, as clearly shown in Figs. 1, 3 and 5, extends upwardly and partly across the outer side face of the ratchet 87 within the circle of revolution thereof. Endwise displacement of the lever 108 from the stud 96 is prevented by a washer 108' that is secured in any suitable manner on the outer end of said stud. This controlling finger 109 has formed on the upper end thereof a rounded projection 110 adapted to be rocked into and out of an operative position coincident or substantially coincident with the axis of rotation of the ratchet 87 and shaft 83. Under certain conditions, the controlling finger 109 acts in conjunction with a controlled finger 111 to prevent engagement of the pawl 86 with the ratchet 87, and under other conditions the controlling finger 109 acts to enable said pawl to engage said ratchet. For these purposes, the pawl 86 has bolted or otherwise suitably secured to the outer side and at the forward end thereof the controlled finger 111 which extends downwardly and partly across the outer side face of the ratchet 87 within the circle of revolution thereof and into position to be acted upon by the controlling finger 109. The controlled finger 111 has formed on the lower end thereof a rounded projection 112 adapted to be engaged by the rounded projection 110 of the controlling finger 109. The rounded projections 110 and 112 of fingers 109 and 111 may alternately move to a position coincident or substantially so with the axis of rotation of ratchet 87 and shaft 83. Thus, when the controlling finger 109 is rocked to the position shown in Fig. 3 of the drawings the rounded projection 110 of said finger is disposed coaxially with the ratchet 87 and shaft 83. The rounded projection 112 of the controlled finger 111 will thus be moved by projection 110 to one side of the axis of the shaft 83 and the pawl 86 will be lifted out of engagement with the ratchet 87. When the controlling finger 109 is rocked to the position shown in Fig. 5 of the drawings the rounded projection 110 of said finger is moved out of coaxial relation with the ratchet 87 and the shaft 83. The rounded projection 112 of the controlled finger 111 will thus move into coaxial relation with said ratchet and said shaft and the pawl 86 will drop into engagement with the ratchet 87.

Oscillating movement is imparted to the lever 108 by the double armed lever 94 to move the controlling finger 109 and shift its rounded end 110 into and out of coaxial relation with the ratchet 87 and shaft 83. For this purpose, the arm 93 of lever 94 has connected therewith at 113 one extremity of a pull spring 114 the opposite extremity of which is connected at 115 with the lever 108. Secured in and projecting laterally from the arm 93 of lever 94 is a pin 116 which engages the lever 108 through an enlarged opening 117 formed therein. Due to the contracting action of the spring 114 the lever 108 is held in engagement with the pin 116 and in proper position relative to the double armed lever 94. It will thus appear that the controlling finger 109 may, through the described connections therefor with the double armed lever 94, be oscillated by the cam 90 and the spring pressed rod 98 to effect engagement of the pawl 86 with and disengagement of the same from the ratchet 87. The operation of the controlling finger 109 is so timed with respect to the oscillation of the

pawl carrier 82 that the projection 110 of said finger is moved into coaxial relation with the shaft 83 to engage projection 112 of finger 111 and lift the pawl 86 out of the ratchet 87 immediately after said pawl carrier begins to move clockwise (Fig. 3). Also, the relative timing of finger 109 and pawl carrier 82 is such that projection 110 moves out of coaxial relation with the shaft 83 to enable the pawl 86 to engage the ratchet 87 before said clockwise movement of the pawl carrier 82 is completed. In this manner the pawl 86 is held out of engagement with the ratchet 87 during the major portion of the clockwise or idle movement of the pawl carrier 82 and insures complete engagement of a tooth of said ratchet by said pawl before said pawl carrier moves counter-clockwise.

When the top of the pile of sheets is at the proper height, the projection 110 of finger 109 is held in coaxial relation with the shaft 83 and in contact with the projection 112 of the finger 111 to thereby prevent engagement of the pawl 86 with the ratchet 87. Under these conditions the pawl carrier 82 is rocked by the described connections therefor with the crank disc 80 and the projection 112 of the controlled finger 111 merely rocks about the projection 110 of the controlling finger 109. In order to normally hold the projection 110 of the controlling finger 109 in coaxial relation with ratchet 87 and shaft 83, the bracket 101 has pivoted thereon at 118 a latch 119 that is urged by a pull spring 120 into engagement with the underside of the sleeve 99 adjacent the flattened portion 104 thereof. The spring 120 has one end connected at 121 with the latch 119 and its opposite end connected at 122 with the bracket 101. It will thus appear that engagement of the latch 119 with the underside of the sleeve 99 holds the rod 98 against downward movement by the spring 105 and thus prevents the roller 91 from following the low part of the cam 90. This, in turn, prevents operation of the double armed lever 94, the lever 108 and the controlling finger 109. The high part of the cam 90 is so proportioned that upon engagement of the same with the roller 91 during each cycle of operation a slight upward movement is imparted to the rod 98 and sleeve 99 thereon to free the latch 119 from the underside of said sleeve and provide for disengagement of said latch from the sleeve in a manner hereinafter described.

Disengagement of the latch 119 from the underside of the sleeve 99 to enable lowering of the rod 98 by the spring 105 and subsequent disengagement of the controlling finger 109, is effected by pile controlled means preferably mounted, constructed and operated as follows. Pivotally mounted on the stud 96 between the double armed lever 94 and the adjacent front head 7 is a bell crank lever 123 one arm 124 of which is curved downwardly and rearwardly and also offset laterally as indicated at 125 (Fig. 4). Secured in the offset portion 125 of the arm 124 is a stud 126 having journalled thereon a roller 127 adapted to also engage the cam 90 at a point in advance of the roller 91 on arm 93. The other arm 128 of bell crank lever 123 has pivotally connected therewith the lower end of a spring pressed rod 130 which extends upwardly through a forked stud 131 that is secured in any suitable manner in the bracket 101. The spring 132 for rod 130 is mounted thereon between the forked stud 131 and a collar 133 secured to said rod.

The upper end of the rod 130 is pivotally connected at 134 with an arm 135 of a bell crank

lever 136 the other arm of which is indicated at 137. This bell crank lever 136 is secured to the outwardly projecting end of a rock shaft 138 (Figs. 2, 3, 5 and 11) that extends transversely of the feeder and is journalled in suitable bearings in one of the front heads 1 and the center bracket 71. The arm 137 of bell crank lever 136 has secured on the lower end thereof a laterally projecting pin 139 adapted to engage the lower end of the latch 119. It will thus appear that the bell crank lever 136, through the described connections therefor with the bell crank lever 123, is cam operated in one direction and spring operated in the opposite direction by the cam 90 and rod 130, respectively, to rock the shaft 138 and move the pin 139 toward and away from the latch 119. Sufficient space is provided between the upper end of the bracket 101 and the adjacent front head 1 to enable rocking of the arm 135 of bell crank lever 136, and the rear side of the adjacent worm gear 89 is recessed to provide sufficient space for rocking of the arm 137 of said bell crank lever.

Fixed on the rock shaft 138 adjacent one side of the center bracket 71 is an arm 140 (Figs. 3, 5 and 11). Connected with the arm 140, as by a ball and socket connection 141, is one end of a link 142 the opposite end of which is connected, as by a similar ball and socket connection 143, with an arm 144. This arm 144 extends across the top of the center bracket 71 and is fixed on the forward end of a square bar 145 which extends longitudinally of the feeder approximately in the center thereof. The forward end of the square bar 145 is turned down to receive the arm 144 and to provide a journal that is rotatable in a bearing formed in a bracket 146 secured in any suitable manner on the center bracket 71. The rear end of the square bar 145 is journalled on a pin 147 adjustably secured in an arm 148 that is fixed on the stay shaft 15. Engaged over and operated by the square bar 145 is an arm 149 provided with a reduced cylindrical hub portion 150 which projects through and is journalled in a suitable bearing formed in a bracket 151. This bracket 151 is bolted or otherwise suitably secured to the housing 152 of the valve mechanism 39 and also serves as a cover plate for said housing to prevent accidental displacement of the valve mechanism from the tubular square bar 42. The arm 149 is held against the bracket 151 and in proper position on the square bar 145 by a collar 153 which is secured on the rearwardly and outwardly projecting end of the reduced hub portion 150 of said arm.

Pivottally connected at 154 with the arm 149 is one end of a link 155 which extends downwardly through a suitable opening formed in a lug 156 provided at one side of a bracket 157 that is bolted or otherwise suitably secured to the underside of the valve housing 152. The opposite end of the link 155 is pivotally connected at 158 with the free end of an arm 159 that is pivoted at 160 on the bracket 157. This arm 159 has pivotally connected therewith at 161 intermediate the ends thereof one end of a link 162 the opposite end of which is pivotally connected at 163 with an arm 164 of a pile height governed lever 165 that is provided with another arm 166 curved downwardly at its front end. Secured in the curved forward end of the arm 166 is a pin 167 having journalled thereon a pile height governed sheet supply testing member or roller 168 adapted to engage the top of the pile of sheets 31.

The lever 165 is pivotally mounted at 169 on one arm 170 of a lever 171 which is pivoted at 172 on the bracket 157 and is provided with another arm 173 curved upwardly at its rear end. 5 Threaded in the curved upper end of the arm 173 is an adjusting screw 174 which engages an abutment 175 formed on the bracket 157 at one side thereof. The adjusting screw 174 is provided with an adjusting head 176 and a lock nut 177 by means of which said screw may be adjusted and locked in adjusted positions. By turning the adjusting screw 174 the arm 170 and the lever 165 thereon may be raised or lowered to adjust the position of the roller 168 with respect to the top of the pile of sheets 31 in accordance with the desired feeding level of the pile. In order to hold the lever 171 stationary and in adjusted positions and the adjusting screw 174 in engagement with its abutment 175, the arm 170 of said lever has connected therewith at 169 a rod 178 which extends upwardly through a suitable opening formed in the bracket 157 and has mounted thereon a heavy push spring 179 located between the underside of the bracket 157 and a collar 180 secured on said rod.

It will thus appear that during each cycle of operation of the feeder the lever 165 will, through the described connections therefor with the rock shaft 138, be lowered by the spring pressed rod 130 to move the roller 168 into engagement with the top of the pile of sheets 31 and raised by the cam 90 to lift the roller 168 out of engagement with said pile. It will further appear that when the roller 168 is lowered and raised as aforesaid, 25 the arm 137 and latch operating pin 139 thereon will be swung toward and away from the latch 119. The spring 132 on rod 130 for lowering the roller 168 into engagement with the top of the pile is assisted by a second spring 181 that is engaged over the link 155 and located between the upper side of the lug 156 and a collar 182 secured on said link. This spring 181 also serves to steady the operation of the roller 168 and to take up any lost motion in the various driving 30 connections for said roller. The operation of the roller 168 is so timed that said roller is lowered into engagement with the top of the pile during separation of each sheet by the separator suction cups 37, and raised out of engagement with said pile prior to and while each separated sheet 35 is forwarded from the pile by the suction sheet forwarding devices 49.

As long as the top of the pile 31 is at a proper height where the sheet separating and forwarding devices 37 and 49 can act to separate and forward sheets from the pile, the roller 168 will, as shown in dotted lines in Fig. 3, be prevented by the pile from moving downwardly a sufficient distance to enable the pin 139 on arm 137 to engage the lower end of the latch 119. The pile of sheets 31, the elevating mechanism and the driving connections for the latter will thus remain stationary because the pawl 86, through engagement of the normally stationary controlling finger 109 with the oscillating controlled finger 111 will, as shown in Fig. 3, be prevented from engaging ratchet 87 and driving shaft 83. Under these conditions the rounded projection 112 of the finger 111 will rock about the rounded projection 110 of the finger 109 as pawl 86 and pawl carrier 82 are oscillated by the crank disk 80 and only an idling movement of the pawl and pawl carrier results therefrom.

When the height of the pile of sheets 31 decreases through removal of sheets from the top

thereof, the pin 139 on arm 137, through increased downward movement of the roller 168, as shown in Fig. 5, is enabled to strike the lower end of the latch 119 and disengage said latch from the underside of the sleeve 99. The arm 93 is then permitted to move downwardly by the expanding action of the spring 105 and engagement of the roller 91 with the low part of the cam 98 whereupon the controlling finger 108 is moved to shift its rounded end 110 out of coaxial relation with the ratchet 87 and the shaft 83 (Fig. 5) and enable the pawl 86 to drop into the ratchet 87 at the back of the first tooth thereon before clockwise turning movement (Fig. 5) of the pawl carrier 82 is completed. The pawl carrier 82 then turns in a counter-clockwise direction (Fig. 5) during which like movement is imparted to the ratchet 87 by pawl 86 to partially rotate shaft 83 and raise the pile elevator and pile of sheets 31 thereon through the described driving connections between said shaft and said elevator.

Upon reverse or clockwise movement of the pawl carrier 82 the arm 93 and rod 98 are again raised through engagement of the roller 91 with the high part of the cam 98 to move the finger 108, shift its rounded end 110 into coaxial relation with the shaft 83, lift and hold the pawl 86 out of engagement with the ratchet 87 and enable the latch 119 to be engaged with the underside of the sleeve 99. Before the arm 93 and rod 98 are raised, however, the roller 127 on arm 124 is engaged by the high part of the cam 98 to raise the roller 168 and swing the pin 139 on lever 137 out of engagement with the latch 119. If the pile of sheets 31 has not been elevated sufficiently, the pin 139 on arm 137, upon subsequent lowering of the roller 168, again strikes and disengages latch 119 from the sleeve 99 and the described operation of the pawl and ratchet mechanism will be repeated until the top of the pile reaches the proper predetermined height. In this event, the pin 139 on lever 137 will be prevented from disengaging the latch 119 from sleeve 99 through failure of the roller 168 to lower a sufficient distance. The pawl carrier 82 and pawl 86 then operate idly, as before described, until the height of the pile again decreases to an extent such as to require further elevation thereof. It is to be noted that due to the particular formation and arrangement of the cam 98 on the crank disk 88 and the relative spacing of the rollers 91 and 127, the operations of the pawl carrier 82, the controlling finger 108 and the roller 168 are synchronized relative to each other and always maintained in such relation. It will be further noted that a single member, the crank disk 88 and the cam 98 formed thereon, controls the operation of the pawl carrier 82, the controlling finger 108, and the sheet supply testing member or roller 168.

Thus far the description has related mostly to the intermittently operated elevator operating mechanism and control means therefor by which the elevator 28, 29 and pile of sheets 31 thereon are raised step by step as sheets are fed off the top of the pile by the described sheet separating and forwarding devices. Upon completion of feeding of sheets from the pile, and in order to continue operation of the feeder, it is necessary to reload the elevator and, as herein shown, rapidly actuated elevator lowering and raising mechanism for this purpose is provided which

mechanism is preferably arranged, constructed and operated as follows.

The platform 44 (Fig. 2) has bolted or otherwise suitably secured thereto the end members 183, 184 of a gear box having a top 185 which, in turn, is bolted or otherwise suitably secured to the members 183, 184 at the upper ends thereof. Bolted or otherwise suitably secured on the top 185 of this gear box is an electric motor 186 supplied with current from any suitable source and controlled in a manner and by means hereinafter described. This electric motor 186 has fixed on the armature shaft 187 thereof a sprocket 188 around which passes a chain 189 that also passes around a sprocket 190 fixed on the shaft 191 of pump 41. It will thus appear that the pump 41 is driven by the motor 186 through the described driving connections therebetween.

20 The shaft 191 extends through the end plates 183, 184 of the gear box and is journalled in suitable bearings therein. Fixed on and driven by the shaft 191 are clutch parts 192, 193 arranged for engagement with and disengagement 25 from clutch parts 194, 195 that are loosely mounted on the shaft 191. Loosely and slidably mounted on the shaft 191 between the clutch parts 192, 193 is a clutch connector 196 having engaged in a groove 197 thereof the upper forked 30 end of an arm 198 that is fixed on a clutch connector actuating rod 199. This rod 199 is slidably mounted in suitable bearings in the end plates 183, 184 of the gear box, and upon actuation of said rod in opposite directions by means hereinafter described, like movement is imparted to the connector 196 to selectively connect the clutch parts 192, 194 or 193, 195, as desired.

Secured to or formed integrally with the clutch part 194 and loosely mounted therewith on the shaft 191 is a gear 200 which meshes with a gear 201 that is fixed on a shaft 202 journalled in suitable bearings in the end plates 183, 184 of the gear box and projecting outwardly from one end thereof. The outwardly projecting end 45 of shaft 202 is journalled in a suitable bearing on a bracket 203 that is bolted or otherwise suitably secured to the platform 44.

Secured to or formed integrally with the clutch part 195 and loosely mounted therewith on the shaft 191 is a gear 204 which meshes with an idler gear 205 that is journalled in any suitable manner on the end plate 184 of the gear box. This idler gear 205 meshes with a gear 206 that is fixed on the shaft 202 within the gear box. The shaft 202 has fixed on the outwardly projecting end thereof a sprocket 207 around which passes a chain 208 that also passes around a sprocket 209 that is fixed on the elevator operating worm shaft 83. Slack in the chain 208 is compensated for by a small sprocket 210 (Fig. 6) engaged therewith and journalled on the upper end of an adjustable arm 211. The arm 211 is adjustably mounted in any suitable manner on the bracket 203 and may be adjusted by an adjusting screw 212 that is also mounted in any suitable manner on said bracket.

It will thus appear that when the clutch parts 193, 195 (Fig. 2) are connected by the connector 196, the motor 186 will, through chain 189, shaft 191, gears 204, 205, 206, shaft 202, chain 208 and worm shaft 83, lower the pile elevator from the raised position to a position at the bottom of the feeder. In this lowered position of the pile elevator, it may be loaded or reloaded with a pile of sheets whereupon by connecting

the clutch parts 192, 194 by the connector 198 the motor 186 will, through the chain 189, shaft 191, gears 200, 201, shaft 202, chain 208 and worm shaft 83, raise the elevator and the pile of sheets thereon to a point where the top of the pile is at proper height for separation and forwarding of the sheets therefrom.

In accordance with the present invention novel, and preferably manually operated, control means are provided for selective operation of the 10 intermittently and the rapidly actuated elevator operating mechanisms; for preventing operation of the elevator by one elevator operating mechanism until the other elevator operating mechanism has been rendered inoperative; and for preventing operation of the elevator by either 15 of the elevator operating mechanisms when testing or adjusting the various operating parts of the feeder or the machine with which it is associated. Said control means is preferably arranged, constructed and operated as follows.

The intermittently actuated elevator operating mechanism is controlled by cam controlled means comprising rods 213 and 214 (Figs. 1, 3 and 5). The rod 213 has its upper end pivotally connected at 215 with the lever 108. Rod 213 has an enlarged lower end 216 guided for vertical movement in a suitable opening formed in a bracket 217. Bracket 217 is pivoted at 218 on one of the front heads 7 and is held fixed in 30 proper position by a clamp screw 219 carried by said bracket and engaged in a suitable threaded opening in the adjacent front head 7.

Rod 214 is guided for vertical movement in a suitable opening formed in bracket 217 and is provided above said bracket and above the head 216 of rod 213 with an enlarged head 220. The lower end of rod 214 is pivotally connected at 221 (Figs. 2, 6 to 9) with a pin 222 projecting laterally from, and secured in any suitable manner to, one arm 223 of a bell crank indicated broadly at 224 and forming part of a control unit for the intermittently actuated and the rapidly actuated elevator operating mechanisms described above. The other arm of the bell crank 224 is indicated at 225 and said bell crank is rotatably mounted on a small stud shaft 226 secured in any suitable manner in opposite side walls of a control unit housing 227. This housing 227 is secured to or formed integrally with a supporting bar 228 that extends between and is secured in any suitable manner to one of the pair of front uprights 5.

The arm 223 of bell crank 224 has pivotally connected therewith, as at 229, a spring pressed rod 230 extending downwardly through a suitable opening in the bottom of the housing 227. The spring 231 for rod 230 is mounted thereon between the bottom of housing 227 and a collar 232 secured on said rod in any suitable manner. The arm 225 of bell crank 224 may be selectively engaged by the flat face 233 or the high part 234 of a control cam which is indicated broadly at 235 (Fig. 10) and controls the cam controlled means comprised by the rods 213, 214. The control cam 235 is disposed within the housing 227 and is fixed in any suitable manner on the reduced end 236 of a shaft 237 which extends within the housing 227 and is journalled in any suitable manner on said housing and the supporting bar 228. The cam 235 and the shaft 237 may be manually operated by a handle 238 secured in any suitable manner on the end of said shaft opposite that extending in housing 227 and carrying said cam. Rotation of the cam 235 in

5 opposite directions is limited by a pin 239 extending in housing 227 and secured in any suitable manner to one side wall thereof. One end of the cam 235 is cut away around a portion of its periphery to provide spaced shoulders 240, 241 which, upon rotation of the cam in opposite directions, contact pin 239 to limit said rotation of the cam.

The rapidly actuated pile elevator lowering and raising mechanism, including the chain 208 and the worm shaft 83, is controlled through the medium of manually operated latch controlled means preferably arranged, constructed and actuated as follows. Disposed within the housing 227 and rotatably mounted on the stud shaft 226 is a latch 242 the upper end 243 of which may be selectively engaged by the low part 244, the flat face 245, and the high part 234 of the cam 235. The latch 242 is provided in its lower end with a 10 hook 246 adapted for engagement with and disengagement from a pin 247 that is secured in any suitable manner on an arm 248. The arm 248 extends within housing 227 through a suitable opening therein and has a hub 249 (Fig. 6) 15 that is fixed on one end of a rock shaft 250. The rock shaft 250 extends through the housing 227 and is journalled in suitable bearings on said housing and the supporting bar 228. Secured to or formed integrally with the hub 249, and disposed outside the housing 227, is an arm 251. The shaft 250 and the arms 248, 251 may be rocked manually by a handle 252 that is fixed on said shaft adjacent its bearing in the supporting bar 228. Interposed between housing 227 20 and the latch 242 is a spring 253 the opposite ends of which are located in suitable openings formed in said housing and said latch. The hub of the bell crank 224 is slotted, as at 254 (Figs. 6 to 9), to receive the upper end of a detent 255 25 that is rotatably mounted on the stud shaft 226. This detent 255 is provided in one edge thereof with a notch 256 adapted for engagement with and disengagement from the pin 247 of arm 248. The lower end of detent 255 has pivotally connected therewith as at 257 one end of a spring 30 pressed rod 258 the opposite end of which extends through a suitable opening in the housing 227. The spring 259 for rod 258 is mounted thereon between the housing 227 and a collar 260 that 35 is secured in any suitable manner on said rod. The arm 251 has pivotally connected therewith, as at 261, the upper end of a link 262 (Figs. 2 and 11). The lower end of link 262 is pivotally connected, as at 263, with one arm 55 of a bell crank 265. The other arm of bell crank 265 is indicated at 266 and said bell crank is rotatably mounted on the shaft 45 that supports one end of the platform 44. The arm 266 of bell crank 265 is pivotally connected, as at 60 267, with a flat outer end of the rod 199 which, as previously described, carries the clutch connector arm 198.

In the normal operation of the feeder, that is, when the elevator and pile of sheets are being 65 raised step by step to compensate for removal of sheets from the top of the pile by the sheet separating and forwarding devices, the parts of the manually operated control means for both the intermittently and rapidly actuated elevator operating mechanisms are in the full line positions thereof shown in Fig. 8 of the drawings. Under these conditions, the rod 214 of the cam controlled means 213, 214, is held in raised position so that the head 220 of the rod 214 is disposed above and in spaced relation with the head 70 75

216 of rod 213, as clearly shown in full lines in Fig. 5 and in dotted lines in Fig. 3 of the drawings. The rod 213 will thus be reciprocated vertically at intervals upon corresponding intermittent operation of lever 93, lever 103, and controlling finger 109, and normal operation of the feeder and separation and forwarding of sheets from the top of the pile will proceed as previously described.

When the pile of supply of sheets is substantially exhausted through separation and feeding of the sheets therefrom and the elevator has correspondingly raised, it is necessary to stop the upward movement of the elevator and reload it with another pile of sheets. This is accomplished in the following manner. The handle 238 is operated to rotate the cam 235 to the full line position thereof shown in Fig. 7 of the drawings. Upon rotation of the cam 235 in this position, the arm 225 of bell crank 224 is moved out of engagement with the flat face 233 of said cam by the high part 234 thereof and said bell crank is rocked to lower the rod 214 and its head 220. Lowering of the rod 214 engages the head 220 thereof with the head 216 of rod 213 so that the latter is held in its lowermost and full line position shown in Fig. 3 of the drawings. This, in turn, holds the lever 103 and controlling finger 109 in the full line position thereof shown in Fig. 3 of the drawings and against movement with the lever 94. In such position of finger 109, its rounded end 110 is disposed substantially coincident with the axis of rotation of ratchet 87 where said rounded end 110 engages the rounded end 112 of the controlled finger 111 and holds pawl 86 out of engagement with ratchet 87. The intermittently actuated elevator raising mechanism is thus thrown out of operation and the carrier 82 and pawl 86 merely reciprocates idly so that no further upward movement is imparted to the pile elevator. When the cam 235 is moved to the full line position thereof shown in Fig. 7 of the drawings to throw the intermittently actuated elevator raising mechanism out of operation, the flat face 245 of said cam is moved into engagement with the upper end 243 of latch 242.

With the intermittently actuated elevator raising mechanism thrown out of operation, the elevator can now be lowered to receive a new pile of sheets. Accordingly, the handle 238 is operated to rotate the cam 235 to the full line position thereof shown in Fig. 9 of the drawings. Upon such rotation of cam 235, the high part 234 thereof still engages the arm 225 of bell crank 224 to hold the rods 213, 214 in full line positions thereof shown in Fig. 3 of the drawings and thus maintain the intermittently actuated elevator raising mechanism out of operation.

The high part 234 of the cam 235, however, upon rotation of said cam to the position shown in Fig. 9 of the drawings, engages the upper end 243 of latch 242, swings the latch about the stud shaft 226, and disengages the hook 246 of said latch from the pin 247. The handle 252 may then be moved downwardly to the dotted line position thereof indicated at D in Fig. 9 of the drawings, such movement of said handle rocking shaft 250 and arms 248 and 251 to the full line positions of the same therein shown. At the same time, the pin 247 is disengaged from the notch 256 of detent 255 through downward movement of the handle 252. When the arm 251 is swung to the full line position thereof shown in Fig. 9 of the drawings, the link 262 is raised, the bell crank 255 is rocked clockwise as viewed in Fig. 2, 75

and the rod 199 and the clutch connector 196 are shifted to the right (Fig. 2) and connect the clutch parts 193, 195. When the clutch parts 193, 195 are connected, the pile elevator is lowered by the motor 186 to the bottom of the feeder through the described connections for said motor with the worm shaft 83 through said clutch parts 193, 195. When the elevator reaches the bottom of the feeder, the handle 252 is moved upwardly to a neutral position thereof indicated at N in Fig. 9 of the drawings and determined by engagement of pin 247 with the notch 256 of detent 255. The parts of the control unit, however, remain in the full line positions thereof shown in Fig. 9 so that operation of the intermittently actuated elevator operating means is prevented while the elevator is lowered and being loaded with a new pile of sheets.

Upon movement of handle 252 to the position N shown in Fig. 9, the clutch connector 196 is moved to the full line position thereof shown in Fig. 2, thus disconnecting the clutch parts 193, 195 and disconnecting the rapidly actuated elevator lowering and raising mechanism from the worm shaft 83. The elevator, having been lowered to the bottom of the feeder as described, is now loaded with a new pile of sheets, whereupon the handle 252 is moved upwardly to the dotted line position thereof indicated at U in Fig. 9 of the drawings. The arm 251 is thus rocked downwardly to the dotted line position shown in Fig. 9 and, through the described connections for said arm with rod 199, shifts said rod and the connector 196 to the left as viewed in Fig. 2 of the drawings. When rod 199 and connector 196 are shifted to the left as viewed in Fig. 2, the clutch parts 192, 194 are connected and the elevator and new pile of sheets are raised by the motor 186 through the described driving connections for said motor with the worm shaft 83 through said clutch parts 192, 194.

When the elevator and pile of sheets have been raised so that the top of the pile is at proper height for feeding of the sheets therefrom, the handle 252 is moved to the position N thereof (Fig. 9) and pin 247 is again engaged with the notch 256 of detent 255. The connector 196 is thus shifted to the full line position thereof shown in Fig. 2, thereby disconnecting clutch parts 192, 194 and disconnecting the rapidly actuated elevator lowering and raising mechanism from the elevator. Under these conditions, the cam 235, the bell crank 224 and the latch 242 remain in the full line positions thereof shown in Fig. 9 of the drawings and operation of the elevator by the intermittently actuated elevator operating mechanism is still prevented by rod 214 through engagement of its head 220 with the head 216 of rod 213.

With the elevator and new pile of sheets raised, the handle 238 is now operated to rotate the cam 235 to the full line position thereof shown in Fig. 7 of the drawings. Upon such rotation of cam 235 the high part 234 thereof continues to engage arm 225 of bell crank 224 so that rod 214 is held down to prevent operation of the intermittently actuated elevator operating mechanism as previously described. At the same time, however, and through rotation of cam 235 to the full line position thereof shown in Fig. 7 of the drawings, the high part 234 of the cam is moved out of engagement with the latch 242 whereupon spring 253 swings said latch about stud shaft 226 so that the upper end 243 of the latch engages the flat face 245 of the cam and the hook

246 of said latch engages the pin 247 of arm 248. The rapidly actuated elevator raising and lowering mechanism is thus again locked to prevent operation thereof whereupon the handle 238 is operated to rotate cam 235 to the full line position thereof shown in Fig. 8 of the drawings. Upon such rotation of cam 235 the flat face 233 thereof is moved out of engagement with the upper end 243 of latch 242 whereupon said upper end 243 engages the low part 244 of the cam and so maintains the hook 246 of the latch engaged with the pin 247 of arm 248. At the same time, the high part 234 of cam 235 is moved out of engagement with the arm 225 of bell crank 224 whereupon the spring pressed rod 230 swings said bell crank so that its arm 225 engages the flat face 233 of the cam and the rod 214 is raised to lift its head 216 out of engagement with the head 218 of rod 213.

With the rapidly actuated elevator operating mechanism locked and the pile of sheets raised, the governor roller 188 can then act to set the intermittently actuated elevator raising mechanism into operation so that the elevator and pile of sheets will be raised step by step as the sheets are separated one after another from the top of the pile and forwarded in like manner therefrom. The operations described above in connection with actuation of the handles 238 and 252 in order to load or reload the feeder are repeated each time a pile of sheets has been completely fed from the elevator and a new pile is loaded thereon for feeding of the sheets therefrom. Further description of these operations is therefore unnecessary. It might be pointed out, however, that releasable locking of the cam 235 in each of its three positions as shown in Figs. 7, 8 and 9 of the drawings is accomplished by a spring pressed ball 268 (Fig. 6) carried in one side wall of the housing 227 and engaging in depressions or sockets 269 (Fig. 10) formed in and suitably spaced around said cam at one end thereof. Likewise, locating of handle 238 in neutral position and pin 247 of arm 248 in alinement with hook 246 of latch 242 is accomplished by the notch 256 in detent 255.

It might further be pointed out that if the cam 235 should accidentally be rotated from the position shown in Fig. 9 to the position shown in Fig. 8 while the rapidly actuated elevator lowering and raising mechanism is being employed, the intermittently actuated elevator raising mechanism could not be thrown into operation for the following reasons. The arm 225 of bell crank 224 has bolted or otherwise suitably secured thereto a block 270 which projects laterally therefrom and across the upper end 243 of latch 242. When the bell crank 224 and latch 242 are moved by the cam 235 to their full line positions shown in Fig. 9 of the drawings, and the handle 238 is moved to the dotted line positions indicated at D and U, the pin 247 of arm 248 is disposed in the path of movement of the latch 242 and prevents said latch from following the cam 235 by the action of spring 258 in the event said cam is accidentally rotated to the position shown in Fig. 8 of the drawings. In this manner, the bell crank 224, due to engagement of block 270 thereof with the upper end 243 of latch 242 is also prevented from following the cam 235 upon accidental rotation thereof as aforesaid, thus holding and maintaining the intermittently actuated elevator raising mechanism inoperative while the elevator is being rapidly raised or lowered. It will therefore appear

that the intermittently actuated elevator raising mechanism may be thrown into operation only after the rapidly actuated elevator raising and lowering mechanism is disconnected through movement of the handle 238 to neutral position indicated at N in Fig. 9 of the drawings, and the hook 246 of latch 242 is engaged with pin 247 of arm 248.

It might further be pointed out that the intermittently actuated elevator raising mechanism may be thrown out of operation at any time during the normal operation of the feeder to discontinue the step by step elevation of the pile when, for example, making adjustments in the feeder, or when it is desired to set, adjust or run the printing or other machine with which the feeder is associated prior to loading of a pile of sheets into the feeder. This is accomplished, while the rapidly actuated elevator lowering and raising mechanism is prevented from being thrown into operation, by operating the handle 238 to rotate cam 235 to the position shown in Fig. 7 of the drawings. The bell crank 224 is thus rocked to lower the rod 214 and engage its head 220 with the head 218 of rod 213. As previously described, engagement of head 220 with head 218 of rod 213 holds the rounded end 112 of the controlling finger 109 substantially coincident with the axis of rotation of ratchet 87 thereby preventing engagement of the pawl 86 with said ratchet during reciprocation of the pawl carrier 82 and thus preventing raising of the elevator by the intermittently actuated elevator raising mechanism.

Referring now more particularly to Fig. 11 of the drawings, the motor 186 employed to drive pump 41 and the rapidly actuated elevator lowering and raising mechanism, is of the three phase type supplied with current from any suitable source through lead wires 271, 272 and 273. Wire 271 is connected by a wire 274 with one terminal of a normally open motor starting switch 275 of the push button type. This switch 275 is arranged in a switch box 276 indicated in broken lines in Fig. 11 and mounted by any suitable means at any convenient point on the feeder frame. The other terminal of switch 275 is connected by a wire 277 with a coil 280 of a magnetic switch 281 arranged in a control box 282 indicated in broken lines in Fig. 11 and secured by suitable means at any convenient point on the feeder frame.

The coil 280, in turn, is connected by a wire 283 with the wire 273 and it will thus appear that when the switch 275 is closed by the machine attendant, the coil 280 will be energized and actuate switch 281 to close it in contact with terminals 284, 295 and 286 of wires 271, 272 and 273. Closing of the switch 281 starts the motor 186 which receives current from wires 271, 272 and 273 through wires 287, 288 and 289 which are connected with said switch and with said motor. The switch 279 having been closed by the machine attendant, is opened by a spring (not shown) as soon as he releases it, thus disconnecting the wires 274 and 277. The wire 277, however, which is connected with the switch 275 and the coil 280, is also connected with the switch 281 by a wire 290. When the switch 281 is closed the wire 290 is connected by said switch with the terminal 291 of a wire 292 which is connected with one terminal of a normally closed stop switch 293. This switch 293 is arranged in a switch box 294 secured in any suitable manner to a bracket 295 that is bolted or otherwise suit-

ably secured on the bracket 71 at one side thereof.

The other terminal of switch 293 is connected by a wire 296 with one terminal of a normally closed motor stopping switch 297 which is of the push button type and arranged in the switch box 276. The other terminal of switch 297 is connected by a wire 298 with the wire 274 which, as previously described, is connected with the lead wire 271. It will thus appear that when the switch 275 is released by the machine attendant and opened by its spring to disconnect wires 274, 271, the coil 280 receives current from the lead wire 271 through wires 274 and 298, switch 297, wire 296, switch 293, wire 292, terminal 291 and wires 290, 277 and 273. The coil 280 thus continues to be energized and maintains switch 281 closed regardless of opening of switch 275. It will further appear, that when either the switch 293 or the switch 297 is actuated to open the same, the previously described current for maintaining coil 280 energized is broken thus causing said coil to be deenergized so that switch 281 is opened and the motor 186 is stopped.

When employing the rapidly actuated elevator lowering and raising mechanism to lift the pile of sheets to proper position for action of the sheet separating and forwarding devices, the machine attendant may fail to stop said mechanism at the proper time with the result that the top of the pile will be raised beyond the proper and predetermined height therefor. Under these conditions it is necessary to lower the elevator and pile of sheets slightly so that the top of the pile is disposed at said proper or predetermined height. Accordingly, pile actuated means which, as shown in Fig. 11 includes a roller 299, is provided to open switch 293, stop motor 186, and discontinue elevation of the elevator and pile by the rapidly actuated elevator lowering and raising mechanism if the pile is raised too high.

When the top of the pile of sheets is at the proper or predetermined height as indicated, for example, in full lines in Fig. 11, the roller 299 is disposed slightly above the top of the pile. The reason for this spacing of roller 299 above the top of the pile is to provide for stream feeding of the sheets therefrom without interference by said roller. The roller 299 is journaled on one arm 300 of a bell crank 301 the other arm of which is indicated at 302. This bell crank 301 is pivoted, as at 303, on the bracket 71. The bracket 71 also has pivoted thereon at 303 a bell crank 304 the arms of which are indicated at 305 and 306. The arm 302 is adjustably connected with the arm 306 by a screw 307 which passes through a slot 308 in said arm 306. The screw 307 and slot 308 connect the bell cranks 301 and 304 for operation thereof as a unit and at the same time enable roller 299 to be adjusted relative to the top of the pile of sheets to obtain the proper or desired spacing therebetween.

The arm 306 of bell crank 304 has pivotally connected therewith, as at 309, one end of a spring pressed rod 310. The opposite end of rod 310 extends through a suitable opening in bracket 295 and said end of the rod has threaded thereon adjusting nuts 311. The spring 312 for rod 310 is mounted thereon between the bracket 295 and a collar 313 secured in any suitable manner on said rod. The bell crank arm 305 is provided with a rounded, enlarged end 314 which is normally held, through the action of spring pressed rod 310, in contact with a roller 315 on switch

293 and in a position such as to enable a spring (not shown) to hold the switch 293 closed.

If the elevator and pile of sheets are raised too high by the rapidly actuated elevator lowering and raising mechanism, the roller 299 will be raised by the top of the pile, as indicated in dotted lines in Fig. 11 of the drawings. The bell crank arms 309, 305 will thus be rocked from their normal full line positions where they are held by spring pressed rods 310 and nuts 311, to their dotted line positions. Under these conditions, the rounded end 314 of arm 305 will depress roller 315 and open switch 293. When switch 293 is open the circuit including the same is broken so that switch 281 is opened, motor 186 is stopped, and further elevation of the elevator and pile of sheets is prevented.

When, as indicated in dotted lines in Fig. 11, the top of the pile of sheets is holding the switch 293 open, it cannot be closed to enable starting of motor 186 and lowering of the elevator and pile to bring the top of the latter down to the proper and predetermined height therefor. In accordance with the present invention, means are provided to start the motor and lower the elevator and pile of sheets to proper position when the switch 293 is opened by the pile, and said means is preferably arranged, constructed and operated as follows.

The bell crank 265 is provided with an enlarged, rounded projection 316 which, in the neutral or latched full line positions of handle 252 and the parts connected therewith shown in Fig. 11, contacts a roller 317 on a switch 318 and enables a spring (not shown) for said switch to normally maintain the same open. This normally open switch 318 is mounted in a switch box 319 that is secured in any suitable manner on a bracket 320. The bracket 320 is bolted or otherwise suitably secured on a stay shaft 33' parallel with the stay shaft 33 and connected in any suitable manner with a pair of the front uprights 5, 5. The terminals of switch 318 are connected by wires 321, 322 with the wires 292, 296 of the described circuit for motor 186.

If the elevator and pile of sheets are raised too high by the rapidly actuated elevator lowering and raising mechanism, the pile of sheets will, as previously described, open switch 293 and stop motor 186 and said mechanism. Switch 293 however, as before stated, cannot now be closed to start the motor, and in order to start said motor, lower the elevator, and bring the pile to proper position, the machine attendant first depresses handle 252 to the lower dotted line position thereof indicated at D in Fig. 11 of the drawings. This disconnects clutch parts 193, 195 (Fig. 2) and, at the same time, causes projection 316 of bell crank 265 to lift roller 317 and close switch 318.

The machine attendant then closes switch 275 whereupon coil 280 is energized and actuates switch 281 to close it in contact with terminals 284, 285 and 286 of wires 271, 272 and 273 and thus start the motor 186, as previously described. Through the motor 186 and the clutch 193, 195 the elevator and pile of sheets is lowered until said pile reaches the proper position whereupon the machine attendant disconnects said clutch and motor from the elevator by moving handle 252 to the full line neutral position N thereof shown in Fig. 11 of the drawings. In accomplishing these results, the machine attendant releases switch 275 which, of course, opens at a time when switch 293 is open. Switch 318,

however, being at that time closed, the coil 280 receives current from lead wire 271 through wires 274, and 298, switch 297, wires 296 and 322, switch 318, wires 321 and 292, terminal 291 and wires 290, 277 and 273. The coil 280 is thus held energized to maintain switch 281 closed and motor 186 in operation regardless of the opening of switches 275 and 293 when switch 318 is closed.

It will of course be understood that when the pile of sheets is lowered to bring the top of the pile to the proper or predetermined height, spring pressed rod 310 returns roller 299 to its normal position and the spring (not shown) for switch 293 closes the latter. Also, it will be understood that when handle 252 is moved to its neutral position N (Fig. 11), projection 316 is lowered and the spring for switch 318 opens said switch. The switch 297 is, of course, employed to stop the motor 186 and the pump 41 whenever this is desirable. When employed for this purpose, switch 297 thereafter closes through the action of its spring (not shown), whereupon motor 186 may be started by switch 215, as previously described.

The operations of step by step elevation of the pile of sheets, separation and forwarding of the sheets from the pile, lowering, loading, and raising the elevator with a new pile of sheets to proper position, and control of all of said operations having been described in detail above, in conjunction with the mechanisms for performing such operations, no further description of the present machine and its operation is necessary. It is pointed out, however, that the present invention may be embodied in types of machines or sheet feeders other than the embodiment herein illustrated and described and it is therefore to be expressly understood that the present invention is not limited to said embodiment or otherwise than by the terms of the appended claims.

What I claim is:

1. In a sheet feeder having sheet supply moving mechanism including a ratchet and a pawl for driving the same, the combination of controlled and controlling fingers each extending partly across one side face of the ratchet within the circle of revolution thereof, a reciprocated actuating carrier for the pawl and the controlled finger and by which said controlled finger is reciprocated relative to the controlling finger, normally inoperative actuating means for the controlling finger normally holding said controlling finger stationary in a position to contact the reciprocating controlled finger and prevent engagement of the pawl with the ratchet, and means for throwing said controlling finger actuating means into and out of operation whereby the controlling finger is moved out of or into said position and said pawl is engaged with or disengaged from said ratchet.

2. In a sheet feeder having sheet supply moving mechanism including a ratchet and a pawl for driving the same, the combination of a controlled finger and a pivoted controlling finger each extending partly across one side face of the ratchet within the circle of revolution thereof, an oscillated actuating carrier for the pawl and the controlled finger and by which said controlled finger is rocked in opposite directions relative to the controlling finger, normally inoperative actuating means for the controlling finger normally holding said controlling finger stationary in a position to contact the rocking controlled finger and prevent engagement of the pawl with the

ratchet, and means for throwing said controlling finger actuating means into and out of operation whereby the controlling finger is rocked out of or into said position and said pawl is engaged with or disengaged from said ratchet.

3. In a sheet feeder having sheet supply moving mechanism including a ratchet and a pawl for driving the same, the combination of controlled and controlling fingers each extending partly across one side face of the ratchet within the circle of revolution thereof, means for actuating the pawl relative to the ratchet and for actuating the controlled finger relative to the controlling finger, means for actuating the controlling finger, latch means normally preventing operation of the controlling finger actuating means and normally holding the controlling finger stationary in a position to contact the actuated and controlled finger and prevent engagement of the pawl with the ratchet, and means for alternately throwing said latch means and said controlling finger actuating means into and out of operation to thereby move said controlling finger out of or into said position and enable said pawl to be engaged with or disengaged from said ratchet.

4. In a sheet feeder having sheet supply moving mechanism including a ratchet, a pawl for driving the same, and an oscillated carrier on which the pawl is mounted for actuation thereby, the combination of a controlled finger mounted on the pawl for rocking movement therewith and extending partly across one side face of the ratchet within the circle of revolution thereof, a controlling finger also extending partly across said side face of the ratchet and within its circle of revolution, a pivoted lever on which the controlling finger is mounted, normally inoperative actuating means for the lever and the controlling finger normally holding them stationary so that said controlling finger is disposed in a position to contact the rocking and controlled finger and prevent engagement of the pawl with the ratchet, and means for throwing said lever and controlling finger actuating means into and out of operation whereby the controlling finger is moved out of or into said position and said pawl is engaged with or disengaged from said ratchet.

5. In a sheet feeder having sheet supply moving mechanism including a ratchet and a pawl for driving the same, the combination of controlled and controlling fingers each extending partly across one side face of the ratchet within the circle of revolution thereof, a reciprocated actuating carrier for the pawl and the controlled finger and by which said controlled finger is reciprocated relative to the controlling finger, cam and spring operated means for actuating the controlling finger, latch means normally preventing finger actuating operation of the controlling finger actuating means and normally holding said controlling finger stationary in a position to contact the controlled and reciprocated finger and prevent engagement of the pawl with the ratchet, and means for alternately throwing said latch means and said controlling finger actuating means into and out of operation whereby the controlling finger is moved out of or into said position and said pawl is engaged with or disengaged from said ratchet.

6. In a sheet feeder having sheet supply moving mechanism including a ratchet and a pawl for driving the same, the combination of cooperatively related controlled and controlling fingers extending across one side face of the

ratchet within the circle of revolution thereof and having opposed rounded ends, a reciprocated carrier on which the pawl and the controlled finger are mounted and thereby actuated, means for actuating the controlling finger normally inoperative and normally holding said controlling finger stationary in a predetermined position with its rounded end in contact with the rounded end of the controlled and reciprocated finger to thereby prevent engagement of the pawl with the ratchet, and means for throwing said controlling finger actuating means into and out of operation whereby the controlling finger is moved out of or into said position and said pawl is engaged with or disengaged from said ratchet.

7. In a sheet feeder having sheet supply moving mechanism including a ratchet and a pawl for driving the same, the combination of cooperatively related controlled and controlling fingers extending across one side face of the ratchet within the circle of revolution thereof and provided with opposed rounded ends alternately movable into a position coincident with the axis of rotation of the ratchet to provide for engagement of the pawl with or disengagement of the same from said ratchet respectively, an oscillated carrier on which the pawl and the controlled finger are mounted and thereby actuated, means for actuating the controlling finger normally inoperative and normally holding said controlling finger stationary with its rounded end in the aforesaid position to contact the rounded end of the controlled and oscillated finger and thereby prevent engagement of the pawl with the ratchet, and means for throwing said controlling finger actuating means into and out of operation whereby the rounded ends of said controlled and controlling fingers are alternately moved into and out of said position and the pawl is engaged with or disengaged from the ratchet.

8. In a sheet feeder having sheet supply moving mechanism including a ratchet and a pawl for driving the same, the combination of controlled and controlling fingers extending across one side face of the ratchet within the circle of revolution thereof and provided with opposed end portions alternately movable into a position substantially coincident with the axis of rotation of said ratchet, a reciprocated carrier for the pawl and the controlled finger and on which they are mounted and thereby actuated, and means for alternately moving the opposed end portions of the controlled and controlling fingers into and out of said position whereby said pawl may be engaged with and disengaged from the ratchet.

9. In a sheet feeder having sheet supply moving mechanism, the combination of means for controlling the operation of the sheet supply moving mechanism comprising a pair of movably mounted fingers having opposed ends alternately movable into and out of a predetermined position to thereby throw said mechanism into and out of operation, and means for actuating said fingers and alternately moving their opposed ends into and out of said position.

10. In a sheet feeder having sheet supply moving mechanism, the combination of means for controlling the operation of the sheet supply moving mechanism comprising a continuously actuated finger and a normally stationary movably mounted finger having opposed ends alternately movable into and out of a predetermined position to thereby throw said mechanism into and out of operation, and means for moving the normally stationary finger toward and away from

the continuously actuated finger whereby the opposed ends of said fingers are alternately moved into and out of said position.

11. In a sheet feeder having sheet supply moving mechanism, the combination of means controlling the operation of the sheet supply moving mechanism comprising a continuously actuated finger and a normally stationary movably mounted finger having opposed ends alternately movable into and out of a predetermined position to thereby throw said mechanism into and out of operation, means for moving the normally stationary finger toward and away from the continuously actuated finger whereby the opposed ends of said fingers are alternately moved into and out of said position, and means under the control of the sheet supply through movement thereof and removal of sheets therefrom for moving the normally stationary finger toward and away from the continuously actuated finger so that the opposed ends of said fingers are alternately moved into and out of said position.

12. In a sheet feeder having sheet supply moving mechanism including a ratchet, a pawl for driving the same, and a reciprocated carrier for the pawl, the combination of a controlling member mounted at one side of the ratchet, a reciprocating lever, connections between the lever and the controlling member enabling the latter to be reciprocated by said lever to effect engagement of the pawl with and disengagement thereof from the ratchet, and means for stopping movement of the controlling member independent of movement of the lever to prevent engagement of the pawl with the ratchet and thereby discontinue operation of the supply moving mechanism.

13. In a sheet feeder having sheet supply moving mechanism including a ratchet, a pawl for driving the same, and a reciprocated carrier for the pawl, the combination of a movably mounted controlling member, a reciprocating lever, a spring and pin connection between the lever and the controlling member enabling the latter to be reciprocated by said lever to effect engagement of the pawl with and disengagement thereof from the ratchet, and means for holding the controlling member against movement with the lever to prevent engagement of the pawl with the ratchet and thereby discontinue operation of the supply moving mechanism.

14. In a sheet feeder having sheet supply moving mechanism including a ratchet, a pawl for driving the same, and a reciprocated carrier for the pawl, the combination of a controlling member pivotally mounted at one side of the ratchet, a reciprocating lever, connections between the lever and the controlling member enabling the latter to be reciprocated by said lever to effect engagement of the pawl with and disengagement thereof from the ratchet, means for automatically throwing the lever into and out of operation, and manually operated means for holding the controlling member against movement during operation of the lever to thereby prevent engagement of the pawl with the ratchet and discontinue operation of the supply moving mechanism.

15. In a sheet feeder having a pile elevator, pawl and ratchet type operating mechanism therefor, and power actuated means controlling operation of said mechanism and said elevator and including a continuously driven cam and a spring pressed rod arranged for operation thereby, the combination of a latch engageable with and disengageable from the cam operated and

spring pressed rod to thereby control the operation of said power actuated means, latch controlling means adapted to contact the latch and disengage it from the cam operated and spring pressed rod, mechanism for continuously moving the latch controlling means toward and away from the latch and including a spring pressed rod actuated by said cam, and pile height governed means actuated by said last named mechanism toward and away from the pile and controlling said latch controlling means and contact thereof with said latch.

16. In a sheet feeder of the type having intermittently actuated elevator operating mechanism for raising a pile elevator step by step and rapidly actuated elevator operating mechanism for quickly lowering and raising said elevator, the combination of selectively operable cam controlled means and latch controlled means for rendering one or the other of said elevator operating mechanisms effective to operate the elevator, and manually operable cam means associated with and controlling selective operation of said cam controlled means and said latch controlled means.

17. In a sheet feeder of the type having intermittently actuated elevator operating mechanism for raising a pile elevator step by step and rapidly actuated elevator operating mechanism for quickly lowering and raising said elevator, the combination of selectively operable cam controlled means and latch controlled means for rendering one or the other of said elevator operating mechanisms effective to operate the elevator, a latch automatically operable to engage and release the latch controlled means and thereby controlling the operation thereof, and means for controlling the selective operation of the cam controlled means and the latch controlled means and comprising manually operable cam means associated with and controlling the operation of said cam controlled means and said latch.

18. In a sheet feeder of the type having intermittently actuated elevator operating mechanism for raising a pile elevator step by step and rapidly actuated elevator operating mechanism for quickly lowering and raising said elevator, the combination of selectively operable cam and spring controlled means and manually operated latch controlled means for rendering one or the other of said mechanisms effective to operate the elevator, a latch operable to engage and release the manually operated latch controlled means and thereby control the operation thereof, and actuating means for the cam and spring controlled means controlling selective operation of said cam and spring controlled means, said actuating means comprising manually operable cam means associated with the cam and spring controlled means and said latch and controlling the operation of the latter.

19. In a sheet feeder having elevator operating mechanism for intermittently raising a pile elevator and elevator operating mechanism for rapidly lowering and raising said elevator, the combination of cam controlled means movable to operative and inoperative positions for rendering one elevator operating mechanism effective or ineffective to operate the elevator, latch controlled means movable to operative and inoperative positions for rendering the other elevator operating mechanism effective or ineffective to operate the elevator, and cam means associated with and controlling movement of the cam con-

trolled means and the latch controlled means, said cam means being movable to first render one of the elevator operating mechanisms ineffective through the medium of said cam controlled means and said cam means being further movable to render the other elevator operating mechanism effective through the medium of said latch controlled means.

20. In a sheet feeder having elevator operating mechanism for intermittently raising a pile elevator and elevator operating mechanism for rapidly lowering and raising said elevator, the combination of cam controlled means movable to operative and inoperative positions for rendering one elevator operating mechanism effective or ineffective to operate the elevator, latch controlled means movable to operative and inoperative positions for rendering the other elevator operating mechanism effective or ineffective to operate the elevator, a latch normally engaged with the latch controlled means to thereby lock the same in its inoperative position, and cam means associated with and controlling movement of the cam controlled means and the latch, said cam means being movable to first render one of the elevator operating mechanisms inoperative through the medium of the cam controlled means and said cam means being further movable to disengage the latch from the latch controlled means and thereby render the other elevator operating mechanism effective through the medium of said latch controlled means.

21. In a sheet feeder having elevator operating mechanism for intermittently raising a pile elevator, and elevator operating mechanism for rapidly lowering and raising said elevator, the combination of cam controlled means movable to operative and inoperative positions for rendering one elevator operating mechanism effective or ineffective to operate the elevator, latch controlled means movable to operative and inoperative positions for rendering the other elevator operating mechanism effective or ineffective to operate the elevator, a latch engageable with and disengageable from the latch controlled means, and cam means associated with and controlling movement of the cam controlled means and the latch, said cam means being movable to first engage the latch with the latch controlled means upon movement thereof to its inoperative position to render one elevator operating mechanism ineffective, and said cam means being further movable to render the other elevator operating mechanism effective through the medium of said cam controlled means.

22. In a sheet feeder of the type having a pile elevator and an electric motor for rapidly raising and lowering the pile elevator, the combination of means for supplying current to the motor and comprising a circuit therefor, a normally closed switch in said circuit and adapted to be actuated by the pile to break the circuit and stop the motor in the event the pile is raised by said motor beyond a predetermined level, a normally open switch in said circuit, and means for connecting the motor with the pile elevator and operable to close said last named switch, complete the circuit, and enable lowering of the elevator by the motor to lower the pile to said predetermined level.

23. In a sheet feeder of the type having a pile elevator and an electric motor for rapidly raising and lowering the elevator, the combination of means for supplying current to the motor and

comprising a circuit therefor, a normally closed switch in said circuit and adapted to be actuated by the pile to break the circuit and stop the motor in the event the pile is raised by said motor beyond a predetermined level, a normally open switch in the circuit, a clutch for connecting the motor with the pile elevator to rapidly lower

said elevator, and means for engaging the clutch and closing said last named switch to complete the circuit, lower the elevator by the motor, and thereby lower the pile to said predetermined level.

EDWIN W. GOODWIN.
